UNITED STATES PATENT OFFICE.

WILLIAM B. BOLSINGER, OF LOS ANGELES, CALIFORNIA.

CARD HOLDER.

Application filed November 30, 1927. Serial No. 236,791.

This invention relates to game apparatus and more particularly to a card holder by means of which playing cards may be supported in an upright position in such relation to each other that the indicating characters of the cards may be readily seen.

One object of the invention is to provide a card holder consisting of an elongated body having grooves formed therein and constituting card-receiving seats, the grooves being so cut that the cards will be disposed diagonally of the carrier and to further permit the cards to face either end of the elongated body.

Another object of the invention is to provide a card holder which will not be liable to turn over when cards are supported in its grooves and also to permit the cards to be very easily inserted or removed from the holder without danger of their being torn or otherwise marred.

The invention is illustrated in the accompanying drawing, wherein

Figure 1 is a top plan view of the improved card holder, and

Fig. 2 is a view showing the card holder in side elevation and cards supported thereby indicated by dotted lines.

The improved card holder consists of an elongated body 1 which is preferably formed from a strip of wood of a suitable length and width but may be formed of metal if so desired. The body may be solid or hollow and, if metal, may be formed of sheet metal. Its upper and lower faces 2 and 3 are flat throughout its length and parallel to each other and its side and end faces 4 and 5 extend at right angles to its lower face. The upper face of the body is of less length and width than the lower face and is joined to the side and end faces by beveled faces 6 and

7 which converge upwardly. It will thus be seen that the portion of the body below the beveled faces 6 and 7 will be of greater width than its upper portion and, therefore, the body will not be liable to be easily tilted when inserting or removing cards and there will be less danger of the cards slipping out of engagement with the body. Grooves 8 and 9 are formed in the body and extend diagonally across its upper face with their end portions opening through the beveled side faces 6 and these grooves are of a depth corresponding to the depth of the beveled faces. By an inspection of Fig. 1, it will be seen that the grooves 8 are parallel and evenly spaced from

each other and extend in crossed relation to the grooves 9 which are also parallel and evenly spaced from each other. Since the grooves 8 and 9 extend at right angles to each other, the cards to be supported may be inserted into either the grooves 8 or the grooves 9 and when so supported will face a selected end of the carrier so that a person may very easily see the cards. By having the cards fitted into the grooves, as indicated by dotted lines in Fig. 2, their indicating characters will be exposed, as clearly shown in this figure, and, therefore, there will be no danger of a person failing to play the proper card by not being able to see all of the cards. The beveled faces not only cause the lower portion of the holder to be of greater width than its upper portion but also permit the cards to be easily fitted into the grooves or removed therefrom without danger of the cards catching in the grooves and becoming torn. Pads 10 are provided so that the support may be placed upon a table without danger of scratching a polished surface. The pads also serve to prevent the holder from slipping out of a desired position upon the table.

Having thus described the invention, I claim:

1. A card holder comprising an elongated body having parallel upper and lower faces and side and end faces extending from the lower face at right angles thereto, the upper portion of the block being beveled from the upper face to intermediate the depth of the side and end faces to form flat bordering faces converging upwardly, said body having grooves formed therein extending transversely across the upper face thereof and opening through the said bordering faces whereby cards may be readily inserted into the grooves and supported therein.

2. A card holder comprising an elongated body having parallel upper and lower faces and side and end faces extending from the lower face at right angles thereto, the upper portion of the block being beveled from the upper face to intermediate the depth of the side and end faces to form flat bordering faces converging upwardly, said body having grooves formed therein extending diagonally across the upper face thereof with their ends opening through the bordering faces and being of a depth corresponding to the bordering faces.

In testimony whereof I affix my signature.
WILLIAM B. BOLSINGER. [L. s.]
